UNITED STATES PATENT OFFICE.

ROBERT M. WILSON, OF NEW YORK, N. Y.

ENVELOP.

No. 797,837.

Specification of Letters Patent.

Patented Aug. 15, 1905.

Application filed April 22, 1904. Serial No. 204,318.

To all whom it may concern:

Be it known that I, ROBERT M. WILSON, a citizen of the United States, residing in the borough of Brooklyn, city of New York, county of Kings, State of New York, have invented certain new and useful Improvements in Envelops, of which the following is a specification, reference being had to the accompanying drawings, wherein—

Figure 1 is an inside face view of the blank from which my improved envelop is made. Fig. 2 is the reverse face of the envelop folded and sealed; Fig. 3, a longitudinal section of Fig. 2 to show the relation of the end flaps; and Fig. 4 shows the reverse face of an envelop, the end flap being torn open, the covered outlines of the flaps shown dotted.

My invention relates to envelops, and more particularly to that form of envelops where a portion thereof is perforated along certain lines, whereby it may be easily opened without irregularly tearing or marring the envelop or damaging the contents.

My object is to provide an envelop of this form which may be entirely opened in one motion, which may be made on the present envelop-machines with only slight changes in the form of the blank, which is made in one piece and which thereby obviates the necessity of using extra pieces of material, and which is so simple in arrangement that it may be used with no additional expense in the making of the cheapest grade of envelops as well as the finest.

To this end my invention consists in certain details of form and arrangement to be more definitely stated in the claims.

In the drawings, where like letters refer to like parts, A designates the front of an envelop of ordinary form, having the end flaps B C, the top or sealing flap D, and the bottom flap E, all made from one piece or blank. The flap D is of the ordinary form and provided with the mucilage-glued margin d. The flap B is approximately of the ordinary form.

In the common form of envelop the flap C would be of the same shape as the other end flap B; but in the blank of my envelop this flap C being smaller and used as an opening-reinforce as well as to close the end of the envelop the lower flap E must be so shaped as to do the work of flap E and to close the remainder of that face of the envelop. To that end the flap E is made with an inclined edge e of about the same contour as that of an or-

inary envelop, but carried beyond the middle in a flattened curve e' to its junction with the straight edge e. This edge e' is a continuation of the edge line of the envelop after it is folded. The flap E at its widest part is of the same width as the envelop, and thus entirely covers the reinforce or opening flap C. e' e'' are two lines of perforations which with the end e inclose a triangular space on the end of flap E, the portions e' of the flap thus inclosed performing a function to be later described. The apex of this triangular figure is formed by a curved or angular slit e'', and the space inclosed within the above-described triangular figure is coated with mucilage, gum, or paste, (indicated by the letter e').

The end flap C is triangular in shape, made in one piece with the body of the blank, and preferably of the same size as the triangular portion e', so that when the envelop is folded, as in Fig. 2, the edges of the flap C will substantially coincide with the lines of perforations e' and slit e''.

In making up the envelop the flaps B and C are folded in, as usual, and the flap E folded over on them, the line of mucilage, gum, or paste e holding it to the flap B, but the whole of the triangular portion e' being stuck to the triangular flap C.

Fig. 2 shows the envelop completely folded and in addition sealed, and the position of the flaps being shown in dotted lines in Fig. 4. So folded and sealed the envelop is of the same form as any ordinary envelop, but differs therefrom in the fact that the end flap C is entirely pasted to the bottom flap E instead of only along the margin.

The function of the slit e'' is to form a tongue which may be grasped by the fingers to open the end of the envelop on the line of the perforations e'. In Fig. 2 I have shown the tongue so formed as projecting upwardly. I have shown it thus for the sake of drawing attention to its function; but normally said tongue does not project beyond the plane of the paper, unless the envelop be bent transversely about on a line with said tongue. Then the tongue will project slightly and may be easily grasped. A tearing action on the tongue will now open the envelop along the lines of the perforations e', thus opening the envelop, as shown in Fig. 4, and leaving a triangular flap at one end of a double thickness of paper.

The necessity of pasting the flap C under-

neath the triangular portion e' is as follows: If there was but one thickness of thin paper forming such triangular section, when the tongue was pulled the paper would tear from the base of the tongue almost straight back to the edge e' instead of following the line of the perforations. This is because the direction of the applied force is not the same as the direction of said perforations and the paper tears in the line of least resistance. By reinforcing it, however, the paper has more resistance to tearing strain than the perforations and the tear follows the angular line. In addition to this when the tongue is pulled the edge of the flap C being immediately beneath the perforations acts as a severing edge to break the paper between them, thus making it additionally certain that a triangular and regularly-shaped flap of full width will be opened out. Indeed, with very thin paper it would not be absolutely necessary to have the perforations e' , as the edge of the flap C, reinforced and made stiff by being gummed to the flap E, would itself cut the paper on the angular lines. It is to be noted in this connection that when the flaps C and E are pasted together the apex of flap C comes just to the slit e' and that therefore the apex of flap C, as well as the apex of the triangular portion e' , forms the opening-tongue, both thicknesses of paper being grasped to open the envelop.

In order that the opening-flap may tear properly, following the cutting lines or perforations, it is necessary that the reinforcing and cutting flap be not gummed to the body of the envelop beyond the tearing-lines, but be gummed to that portion only of the envelop within the cutting-lines, preferably over the entire area inclosed within said lines, but at any rate along the lines; otherwise the material on one side of the cutting edge is as strong as the material on the other, and it is as if the envelop were simply made of two thicknesses of material, as far as tearing is concerned. Again, it is necessary to a proper opening of the envelop that the cutting edges of the cutting-flap extend back to that edge of the envelop-body which is to form the base of the opening-flap and that the reinforce so given be beneath that part of the envelop which is to be torn open, else the tear or cut will not diverge to the corners of the envelop, but will be parallel to the line of applied force, and the edges of such reinforcing-flap should extend back to the edge of the envelop which forms the base of the flap in order that the cut may be regular along its entire length. Preferably the reinforcing cutting-flap is of a triangular shape, extending to the corners of the envelop, so that the envelop may be opened to its entire width.

The advantages of my improved envelop are obvious. It is easily opened at one motion of the hand, and the opening of it leaves

a protecting-flap still attached to the envelop. The opening of the envelop does not tear away any portion. Thus there is no danger of the contents being injured or torn. The opening made by severing the flap is of the full width of the envelop and does not require to be made larger in order to get out the contents.

A particular and important advantage lies in the fact that the blank is in one piece only, of a shape easily formed, necessitating no material changes in the ordinary envelop-making machines, and requiring the addition of no supplementary and extra reinforcing or cutting pieces in order to make it operative and complete. Again, the gumming is all on one side of the blank, as in ordinary envelops, thus making it practical to manufacture with machines already in the market.

While I have shown the blank as adapted to an oblong envelop and one whose end it is desired to open, it will be obvious that the principle of my invention may be applied as well to envelops of other shapes and to flaps opening on any other of the four sides. Also it will be understood that the exact figure given to the various flaps may be varied without departing therefrom.

Having described my invention, what I claim is—

1. An envelop having a reinforcing cutting-flap made in one piece with the body of the envelop and turned in from one of its side edges, and a covering-flap turned in from another of its side edges, the said reinforcing cutting-flap lying wholly beneath that portion of the envelop designed to be torn open, and the said covering-flap being provided with a slit whereby the reinforcing cutting-flap may be grasped, substantially as described.

2. An envelop having a reinforcing cutting-flap made in one piece therewith, and a covering-flap adapted to be folded over upon the said cutting-flap, the said cutting-flap lying wholly beneath that portion of the covering-flap designed to be torn open and being gummed thereto, and the said covering-flap having perforations coincident with the edge of the cutting-flap and a slit whereby the cutting-flap may be grasped, substantially as described.

3. An envelop-blank having a sealing-flap with a gummed inside margin, triangular flaps at the ends of the blanks, and a bottom flap, said bottom flap being gummed on one side margin for engagement with one of the side flaps and having a triangular gummed portion on its inside face adapted to cover and be gummed to the other of the end flaps, said bottom flap having a slit forming the apex of the triangular gummed portion, substantially as described.

ROBERT M. WILSON.
